UNITED STATES PATENT OFFICE.

GEORGE N. STEERE, OF HAMILTON, RHODE ISLAND.

DESIGN FOR TAPE.

SPECIFICATION forming part of Design No. 22,119, dated January 10, 1893.

Application filed October 10, 1892. Serial No. 448,458. Term of patent 7 years.

To all whom it may concern:

Be it known that I, GEORGE N. STEERE, a citizen of the United States, residing at Hamilton, in the county of Washington and State 5 of Rhode Island, have invented and produced a new and original Design for Tape, of which the following is a specification, reference being had to the accompanying drawing, showing a part thereof.

10 The figure is a view of a piece of tape having my design thereon.

The leading feature of the design consists in a number of dots or dashes on a tape arranged around a central dot or dash at vari-

ous points throughout the length of the tape, ¹⁵ and it also consists in short diagonal ribs extending throughout the length of the tape.

A represents a tape, B the outer series of dots or dashes, C the center dot or dash and D the diagonal ribs. ²⁰

What I claim as new and desire to secure by Letters Patent is;

The design for tape, substantially as shown and described.

GEORGE N. STEERE.
